UNITED STATES PATENT OFFICE.

CARL A. FRAHM, OF CANTON, OHIO, ASSIGNOR, BY MESNE ASSIGNMENTS, TO UNITED ALLOY STEEL CORPORATION, OF CANTON, OHIO, A CORPORATION OF NEW YORK.

SHEET-TRIMMING MACHINE.

Application filed July 1, 1921. Serial No. 481,783.

To all whom it may concern:

Be it known that I, CARL A. FRAHM, a citizen of the United States, residing at Canton, in the county of Stark and State of Ohio, have invented new and useful Improvements in Sheet-Trimming Machines, of which the following is a specification.

The invention relates to machines for trimming the ends of metal sheets; and the object of the improvement is to provide an automatic machine which will truly trim each end of the sheet, and may be adjusted for trimming sheets of different predetermined lengths.

15 The manufacture of expanded metal lath or the like frequently leaves the sheets with ragged or irregular ends, and when such a sheet is made with unexpanded ribs longitudinally located between expanded zones, it may be desirable, if not necessary, to square the ends of the sheets by trimming off protruding portions resulting from the expanding operations.

20 The present invention involves the use of a shearing head with parallel shearing blades operating between parallel shearing dies, a sliding pin clutch for operating the shearing head, means for feeding a sheet to and from the machine, with a forward trip arm actuated by the forward end of the sheet for trimming the same end by the forward shearing blade, and a rear trip arm actuated by the same end of the sheet for trimming the rear end of the sheet to a pre-determined length by the rear shearing blade.

25 A preferred embodiment of the machine is illustrated in the accompanying drawings forming part hereof, in which—

30 Figure 1 is a plan view, in two sections, of the trimming machine;

Fig. 2, an enlarged side elevation of the operating mechanism;

35 Fig. 3, an enlarged plan of the operating mechanism;

Fig. 4, a side elevation section of the operating mechanism, on line IV—IV, Fig. 3;

Fig. 5, a longitudinal section of the trimming mechanism, on line V—V, Fig. 1;

40 Fig. 6, a cross section on line VI—VI, Figs. 2 and 3, showing the trimming mechanism in front elevation;

Fig. 7, a cross section on line VII—VII, Fig. 2;

Fig. 8, a fragmentary perspective view of 65 the rear trip arm and the adjacent guides;

Fig. 9, an inside elevation of the same;

Fig. 10, a cross section of the same on line X—X, Fig. 9; and

Fig. 11, a fragmentary perspective view 60 of the forward trip arm.

Similar numerals refer to similar parts throughout the drawings.

The trimming mechanism includes a shearing head 1, and shearing dies 2 and 2' 65 on opposite sides of the tread, the same being mounted between standards 3 upon a base 4. The trimming head may be operated upward and downward between the shearing dies by well known means, as a 70 cross head 5, guides 6; a pitman 7, a crank shaft 8; a slide pin clutch 9, and a driven pulley 10, arranged as shown in Fig. 6.

Parallel shearing blades 11 and 11' are secured on the opposite sides of the shearing 75 head, and the edges of these blades are adapted to cooperate with the edges of the parallel shearing dies 2 and 2' for successively trimming the forward and rear end of a sheet as it is fed through the machine. 80

The feed-in conveyor may include a series of pairs of disk rolls 12 and 12' driven by a gearing 13 and operating on the ribs of an expanded metal sheet 14 to feed the same into the forward side of the shearing mechanism; and these rolls may be supplemented by parallel guides 15 in a well known manner. The feed-out conveyor may include a series of pairs of rolls 16 driven by the gearing 17 and operating on the expanded zones of the sheet to feed the same 85 from the slitting mechanism.

The forward trip arm 18 may have a trip block 19 with a roughened forward face on its lower end, and is formed or secured on 90 the forward end of a rock sleeve 20 having another rock arm 21 on its other end; which rock sleeve 20 is mounted for rotating and sliding endwise upon the forward trip shaft 22, which in turn is mounted for rotating 100 and sliding endwise in bearings 23 secured to the frame of the machine.

The rock arm 18, normally extends downward and inward so that the trip block 19

will be in the path of one edge portion of the sheet to be trimmed, which may be the rib along one side of an expanded sheet; and a roller 24 is preferably mounted on a pivot pin extending directly inward from the end of the trip arm 18 adjacent to the inner lower side of the trip block 19.

A weight 25 is suspended from the rock arm 21 on the rear end of the trip sleeve 20, and tends to hold the trip arm 18 in normal position with the trip block 19 in the path of the edge of the sheet, while permitting the sleeve to be rotated to swing the trip block to one side of the same; the rotation of the sleeve by the weight being normally stopped by the engagement of the pin 26 on the rock arm 21, with a pin 27 on the hub 28 of the crank arm 29, mounted for rotating and sliding endwise upon the shaft 22 at the rear end of the trip sleeve 21, as shown in Fig. 11.

The crank arm 29 is connected by the rod 30 with a lever 31 which is fulcrummed at 32 on the side of the standard 3, which lever is normally pulled downward by the spring 32' connected with the standard 3, and is provided with a roller 33 riding on the periphery of the cam 34 on one end of the crank shaft 8.

A flange 36 is secured on the forward trip shaft 22 at a convenient place in front of the standard of the shearing mechanism, in rear of which flange is located the inner end of a transverse bar 37, secured to the upper end of the lever 38, the lower end of which lever is secured to a transverse rock shaft 39, on the other end of which shaft is secured a crank arm 40, which is connected by the bar 41, the crank shaft 42 and the bar 43 with the clutch 9, for actuating the same; the parts being so arranged that a rearward movement of the forward trip shaft 22 will cause the flange 36 to impinge the bar 37 and move the same rearward for actuating the clutch to give the crank shaft one rotation, which moves the shearing head downward for a shearing operation and thence upward into normal position.

The rearward movement of the forward trip shaft 22 is resisted by the coiled compression spring 44 in the tubular guide 45 extended from the rear end of the shaft, and the piston 46 bearing against the spring in the rear end of the tubular guide; which piston is secured on the forward end of a rod 47 secured at its rear end to a bearing on the frame of the feed-out conveyor.

A collar 48 is secured to the forward trip shaft 22 adjacent to the rear side of the hub 28 of the crank arm 29 thereon and at an interval in front of one of the shaft bearings 23, and another collar 49 is secured to the same shaft adjacent to the rear end of the same bearing; which collars serve as

stops to limit the longitudinal movement of the shaft, and are so located that a forward movement of the shaft caused by the action of the compression spring 44 will be stopped with the trip block 19 in normal position for actuating a trimming of the forward end of a sheet; and a rearward movement of the shaft will be stopped just as soon as the forward trip mechanism has performed its actuating operation.

Most of the mechanism thus far described is concerned primarily with the operation of trimming the forward end of a sheet delivered to the trimming mechanism by the feed-in conveyor. As the forward end of the sheet travels upon and over the forward shearing die 2, it is preferably directed and held downward upon the same by suitable guides 50; and as the sheet advances, one corner thereof impinges the trip block 19 and acting through the trip sleeve 20 and the crank hub 28 against the collar 48, moves the forward trip shaft rearward so that the flange 36 on its forward end impinges and moves the bar 37 rearward, which actuates the clutch and causes the shearing head 1 to descend and trim the advance end of the sheet by the co-operation of the forward shearing blade 11 and the forward shearing die 2; the sheet being stopped during the shearing operation, by the contact of the collar 48 with the forward end of the bearing 23, during which stopping the feed-in rolls 12 slide upon the sheets.

The sheared off end of the sheet falls downward into the base of the machine, and the descending trimming head impinges the inner side of the trip arm 18, thereby deflecting the trip block 19 outward to clear the side of the sheet by a rotation of the trip sleeve 20 upon the shaft 22. During the upward operation of the shearing head, the cam 34 acts upon the roller 33 to raise the lever 31, the connecting bar 30 and the crank arm 39, to rotate the trip sleeve and hold the trip arm 18 and block 19 clear of the side of the sheet; whereupon the sheet is promptly moved forward by action of the feed-in rolls and passes on to the feed-out conveyor.

Just as soon as the trip block 18 has been swung outward to clear the edge of the sheet, the forward trip bar 22 and the tripping device mounted thereon, are promptly moved forward into normal position by action of the compression spring 44, and when the sheet moves rearward, the roller 24 preferably rides against the edge of the sheet for holding the trip block and trip arm clear of the same. Just as soon as the rear end of the sheet has passed beyond the trip arm, the same swings inward into normal position by action of the weight 25.

As the sheet proceeds rearward, its forward end is guided on to the rear shearing

die 2' by means of an inclined plate guide 51 mounted on the upper ends of the supporting bars 52, operating in upright tubular guides 53 and having heads 54 on the lower ends secured on the ends of the transverse bar 55 resting on the fingers 56 extending forward from the rock shaft 57 supported in bearings 58 and provided with an arm 59 extending rearward, which arm is normally held downward by the spring 60 thereby holding the inclined guide plate 51 upward in proper position for directing the end of the sheet on to the rear shearing die 2'.

15 Guide bars 61 are preferably provided at the forward end of the feed-out conveyor for holding the sheet down upon the rear shearing die; and as the sheet moves rearward, it is engaged by the feed-out rolls 16, 20 and conveyed away from the shearing mechanism.

The rear trip arm 62 is secured upon the rear trip shaft 63, which is rotatable and endwise movable in bearings 64 and 64' 25 mounted on the frame of the feed-out conveyor.

The rearward movement of the rear trip shaft 63 is resisted by the expansion spring 65 which connects it with the frame of the feed-out conveyor, and upon its rear end is secured a gear rack 66 meshing with a gear pinion 67 on the rear end of the forward trip shaft 22, so arranged that one shaft can move endwise with reference to the other, 35 while a rotation of the one shaft will be communicated to the other.

The inner end of the rear trip arm 62 is curved downward to form the trip plate 68 normally resting upon the bottom of the rear feed-out conveyor in the path of the edge portion of the sheet.

40 A connecting bar 69 is pivoted at its rear end to a post 70 secured to the rear trip shaft, and at its forward end is provided with a slotted head 71 engaging the outer end of the bar 37 extending from the upper end of the lever 38 by means of which the clutch 9 may be actuated as described above.

The normal position of the slotted head 45 is with the forward end of the slot in engagement with the transverse bar, so that a rearward movement of the connecting rod 69 serves to actuate the clutch, while the slot permits the cross bar 37 to move rearward when the forward trip is operated without affecting the rear trip.

An angle plate 72 is preferably provided, 50 having its lower flange secured to the bottom of the feed-out conveyor in front of the trip arm 62 and its upright plate 72' curved at its forward end to form a guide for the edge of the sheet. Upon this upright flange is slidably mounted an angle plate with its overlapping flange 73 secured by bolts 74 through slots 75, permitting a limited end-

wise movement; and its other flange 76 is provided with an upright tongue 77 on its forward end which is connected to the trip arm 62 by a bar 78, and its forward end is deflected downward to form a support, to which is connected the rear end of a guide plate 80 having its forward end curved upward in rear of the upright tongue 77 thereby forming an upper guide for the edge portion of the sheet.

75 As the sheet is moved rearward by the feed-out conveyor, the corner or edge portion of the advance end impinges the trip plate 68 and carries it with the rear trip bar 63 and the connecting bar 69 rearward, thereby actuating the clutch for operating the shearing head to trim the rear end of the sheet by the co-operation of the rear trimming blade with the rear trimming die, the sheet being stopped by the abutment of the rear end of the gear rack 66 against the adjacent bearing 64. During this operation the inclined guide 51 is pushed downward by the shearing blade 11', against the action of the spring 60, which reacts to return the guide plate into normal position just as soon as the shearing head is moved upward after trimming the sheet; whereupon the cut-off end of the sheet drops downward into the base of the machine.

90 As the shearing head raises after trimming the rear end of the sheet, the action of the cam 34 raises the crank arm 29 which rotates the forward trip shaft one way and the rear trip shaft the other way, and raises the rear trip arm and swings the trip plate upward out of the path of the sheet; whereupon the sheet, which has been stopped during the shearing operation, moves forward and is delivered from the machine by action 95 of the rolls 16.

100 The rear trip arm 62 is adjusted longitudinally on the rear trip shaft 63 so as to shear the rear end of the sheet at a predetermined length, and a series of angle guide plates as shown in Fig. 8, may be secured at spaced intervals along the feed-out conveyor for co-operating with the trip arm 62 for trimming sheets of different lengths. During each tripping operation, the guide plate 110 80 follows the trip plate 68 rearward, and prevents the pressure of the sheet from bending or deflecting the corner of the sheet upward against the trip plate when it stops the sheet for the trimming operation; or with the trip plate when it is raised to clear the sheet.

115 When ribbed sheets are trimmed, the shearing blades are provided with corresponding grooves, for receiving the ribs, so that the ribs are sheared at the same time as the flat portion of the sheet; and the shearing edges on the punch blades are preferably inclined from the middle to the sides, 120 125 to give them a shearing action.

I claim:-

1. A sheet trimming machine including a reciprocating head with shearing edges on opposite sides, shearing dies co-operating with the shearing edges and two independently operated trip mechanisms for controlling the operation of said head. 70
2. A sheet trimming machine including a reciprocating head with shearing edges on opposite sides, shearing dies co-operating with the shearing edges, means moving a sheet over the shearing dies, mechanism operating the head to trim the ends of the sheet on the respective dies and two trip devices for controlling the operation of said mechanism, one of said devices being adjustable with respect to the other device. 75
3. A sheet trimming machine including a reciprocating head with shearing edges on opposite sides, shearing dies co-operating with the shearing edges, means moving a sheet over the shearing dies, mechanism actuated by the movement of the sheet operating the head for trimming the ends of the sheet on the respective dies and two independent trip devices for controlling the operation of said mechanism. 80
4. A sheet trimming machine including a reciprocating head with shearing edges on opposite sides, shearing dies co-operating with the shearing edges, means moving a sheet over the shearing dies, mechanism for operating the head to trim the ends of the sheet on the respective dies including a trip arm beneath said head for stopping the sheet and actuating the mechanism for trimming the forward end of the sheet. 85
5. A sheet trimming machine including a reciprocating head with shearing edges on opposite sides, shearing dies co-operating with the shearing edges, means moving a sheet over the shearing dies, mechanism for operating the head to trim the ends of the sheet on the respective dies including a trip arm arranged to be engaged by the sheet after it has passed beyond said dies for stopping the sheet and actuating the mechanism for trimming the rear end of the sheet. 90
6. A sheet trimming machine including a reciprocating head with shearing edges on opposite sides, shearing dies co-operating with the shearing edges, means moving a sheet over the shearing dies, mechanism for operating the head to trim the ends of the sheet on the respective dies including a trip arm and longitudinally adjustable means for stopping the sheet after its front end has passed beyond said dies and actuating the mechanism for trimming the rear end of the sheet at a predetermined length. 105
7. A sheet trimming machine including a reciprocating head with shearing edges on opposite sides, shearing dies co-operating with the shearing edges, means moving a sheet over the shearing dies, mechanism for 110
8. A sheet trimming machine including a reciprocating head with shearing edges on opposite sides, shearing dies co-operating with the shearing edges, means moving a sheet over the shearing dies, mechanism for operating the head to trim the ends of the sheet on the respective dies including trip arms for successively stopping the sheet and actuating the mechanism for first trimming the forward end and then trimming the rear end of the sheet at a predetermined length. 115
9. A sheet trimming machine including a reciprocating head with shearing edges on opposite sides, shearing dies co-operating with the shearing edges, means moving a sheet over the shearing dies, mechanism for operating the shearing head including a trip arm normally in the path of the sheet for stopping the same and actuating the mechanism and means for adjusting said trip arm longitudinally with respect to the direction of movement of said sheet. 120
10. A sheet trimming machine including a reciprocating head with shearing edges on opposite sides, shearing dies co-operating with the shearing edges, means moving a sheet over the shearing dies, and a mechanism for operating the shearing head including a trip arm normally in the path of the sheet for stopping the same and actuating the mechanism, and means holding the trip arm free of the sheet during the return movement of the head. 125
11. A sheet trimming machine including a reciprocating head with shearing edges on opposite sides, shearing dies co-operating with the shearing edges, means moving a sheet over the shearing dies, and mechanism for operating the shearing head including a trip arm normally in the path of the sheet for stopping the same and actuating the mechanism and means actuated by the operating mechanism for swinging the trip arm from the path of the sheet during the return movement of the head. 130
12. A sheet trimming mechanism including a reciprocating head with shearing edges on opposite sides, shearing dies co-operating with the shearing edges, means moving a sheet over the shearing dies, mechanism for operating the head to trim the ends of the sheet on the respective dies and yielding means guiding the forward end of the sheet on to the rear shearing die. 135
13. A sheet trimming machine including a reciprocating head with shearing edges on opposite sides, shearing dies co-operating with the shearing edges, means moving a sheet over the shearing dies, mechanism for

operating the head to trim the ends of the sheet on the respective dies including a slide pin clutch, and trip arms for alternately stopping a sheet and actuating the clutch to operate the shearing head for trimming the forward and rear ends of the sheet.

14. A sheet trimming machine including a reciprocating head with shearing edges on opposite sides, shearing dies co-operating with the shearing edges, means moving a sheet over the shearing dies, mechanism for operating the head to shear the ends of the sheet on the respective dies, including endwise movable rotatable trip shafts geared 10 for relative endwise movement.

15. A sheet trimming machine including a reciprocating head with shearing edges on opposite sides, shearing dies co-operating with the shearing edges, means moving a sheet over the shearing dies, mechanism for operating the head to trim the rear end of the sheet including a trip plate impinging a forward corner of the sheet for stopping the same and actuating the trimming mechanism, and a sliding guide moving with the trip plate for the corner portion of the sheet.

16. In a machine for trimming ribbed expanded metal lath, two oppositely disposed stationary shearing dies, a reciprocating head having co-operating shearing dies, clutch means for controlling the operation of said head, rib guides leading to said dies, means for feeding a ribbed expanded sheet along said guides to said dies, a yielding trip stop for stopping said sheet and operating said clutch, rib guides leading away from said dies, and means for feeding a trimmed sheet along said latter guides.

17. In a machine for trimming ribbed expanded metal lath, upper and lower shearing dies, a clutch for controlling the operation of the upper die, means for feeding a ribbed sheet to said dies, a trip stop for stopping said sheet and operating said clutch, guiding means beyond said dies, and another trip stop adapted to be engaged by a rib to actuate said clutch.

18. In a machine for trimming ribbed expanded metal lath, rib feeding means at one end of the machine, mesh feeding means at the opposite end of the machine, stationary and reciprocable cutters located between the same, and automatic means for starting and stopping the said reciprocable cutters, including two independently operable stop trip devices engaged by the sheet to be trimmed.

19. In a machine for trimming ribbed expanded metal lath, means for feeding an expanded metal sheet into the machine, trimming cutters, means for actuating said cutters, a trip stop for stopping the sheet to trim the front end at the proper place, and a second trip stop for stopping the sheet 65 and trimming the rear end at the proper

place with respect to the length of the sheet.

20. In an expanded metal trimming machine, shearing cutters, means for feeding a sheet to said cutters, means for feeding a sheet away from said cutters, two automatic trip stopping devices for stopping the sheet, and means actuated thereby for operating the said cutters to trim the opposite ends of the sheet. 75

21. In an expanded metal trimming machine, shearing cutters, means for feeding a sheet to said cutters, means for feeding a sheet away from said cutters, two automatic trip stopping devices for stopping the sheet, means actuated thereby for operating the said cutters to trim the opposite ends of the sheet, and a geared connection between said trip stop devices. 80

22. In an expanded metal trimming machine, continuously operable means for feeding a sheet, oppositely disposed stationary cutters, a reciprocating head, cutters carried thereby for co-operating with the stationary cutters, and two trip stop devices connected 90 to each other and adapted to be actuated by the sheet. 85

23. In a machine for trimming a ribbed expanded sheet, rib guides, rib feeding discs, a cutter head, means for actuating the same, a clutch for controlling the actuating means, a trip actuated by a rib of the sheet for stopping the sheet and releasing the clutch, and means actuated by the cutter head for retracting said trip. 95

24. In a machine for trimming a ribbed expanded sheet, rib guides, rib feeding discs, a cutter head, means for actuating the same, a clutch for controlling the actuating means, a trip actuated by a rib of the sheet for 105 stopping the sheet and releasing the clutch, means actuated by the cutter head for retracting said trip, and means connected to the trip for engaging the sheet as it moves to hold the trip retracted. 110

25. In a machine for trimming an expanded sheet, continuously operable friction means for feeding a sheet, a reciprocating cutter, means for actuating the same including a trip stop actuated by said sheet, 115 and a roller carried thereby for engaging the sheet to hold said stop out of the way while said sheet is traveling.

26. A machine for trimming an expanded metal sheet, comprising means for frictionally feeding a sheet, reciprocating cutters for trimming the front and rear ends of the sheet, two yielding trip stops, and means of connection between the same. 120

27. In a machine for trimming an expanded metal sheet, means for frictionally engaging the sheet to feed the same, a reciprocating head and cutter for trimming the front end of the sheet, a yielding trip stop normally in the path of the sheet for 130

stopping the sheet, and means actuated thereby for moving said cutter head to trim the sheet, said head engaging said stop to retract the same and permit the sheet to move as soon as said head is raised.

28. In a machine for trimming an expanded metal sheet, means for frictionally engaging the sheet to feed the same, a reciprocating head and cutter for trimming the front end of the sheet, a yielding trip stop normally in the path of the sheet for stopping the sheet, means actuated thereby for moving said cutter head to trim the sheet, said head engaging said stop to retract the same and permit the sheet to move as soon as said head is raised, and a second trip stop actuated by the sheet and retracted by the movement of said head.

29. In a machine for trimming ribbed expanded metal lath, a plurality of guides for directing the ribs of a sheet continuously

driven rolls for engaging the ribs and feeding them along the guides, a stationary shearing die, a reciprocating head, a die co-operating therewith, means for actuating said head, a trip stop for stopping the sheet and releasing said actuating means, rib guides leading away from said head and dies, and friction rolls for engaging the sheet between said guides to feed the sheet away from said dies.

30. A machine for trimming an expanded metal sheet, comprising continuously operating means for frictionally engaging a sheet to feed the same, stationary shearing dies a reciprocating head, dies carried thereby and co-operating with the stationary dies, and mechanism for actuating said head, including two connected trip stop devices located on opposite sides of said head and actuated by the sheet and by said head.

CARL A. FRAHM.
